TYPEWRITING MACHINE

Henry J. Hart, West Hartford, Conn., assignor to
 Royal Typewriter Company, Inc., New York,
 N. Y., a corporation of New York

Application January 9, 1936, Serial No. 58,405

6 Claims. (CL 197—183)

This invention relates to new and useful improvements in typewriting machines generally, although more particularly to abutments or anvils for the type bars and to the method of forming the same.

The principal objects of the invention are to provide an abutment which will reduce the noise made by a type bar contacting the same, and to provide a novel method of forming the parts thereof and assembling the same.

With these and other objects in view which will more fully appear, the nature of the invention will be more clearly understood by following the description, the appended claims, and the several views illustrated in the accompanying drawing.

In the drawing:

Figure 1 is a front elevation of a type bar segment showing the application of my invention thereto.

Figure 2 is an enlarged vertical section taken therethrough.

Figure 3 is an enlarged detail section taken on the line 3—3 of Figure 1.

Figure 4 is an enlarged cross section of the cage.

Figure 5 is a perspective view of the rear plate of the cage.

Figure 6 is a perspective view of the anchor plate of the cage.

Figure 7 is a perspective view of the type bar guide.

Figure 8 is a perspective view of the cage.

Figure 9 is a perspective view of one of the filler plates.

Figure 10 is a perspective view of the front plate of the cage, and

Figure 11 is a perspective view of the guard plate.

Referring to the accompanying drawing, the segment A is formed along its lower portion with the usual radially extending slots 5 for receiving the heels of type bars 6 which are pivoted on the wire 7. The central portion of the segment

A above the type bar pivots is formed in its front face with a recess 8 which includes an arcuate undercut lateral wall 9. Attached to the rear face of the segment by screws 10, is the usual type bar guide 11.

My improved type bar abutment includes an arcuate cage B and one or more arcuate filler plates C mounted therein and forming a resultant laminated unit.

The cage B includes spaced front and rear ar-

cuate steel plates 12 and 13 respectively. The rear or attaching plate 13 is provided along its upper edge with spaced recesses 14, and along its lower edge with spaced recesses 15, the recesses 14 and 15 being disposed in staggered relation. 5 The rear plate 13 is also provided with spaced and upwardly extending attaching ears 16 which are disposed intermediate the recesses 14. Rigidly secured to the front face of the attaching plate 13, by welds 17 or other suitable means, is 10 an arcuate anchor plate 18 which is substantially coextensive with but narrower than the plate 13. The upper edge of the plate 18 lies flush with the upper edge of the plate 13 and consequently the recesses 14 are covered by the plate 18. The lower edge of the anchor plate 18 is disposed above and in spaced relation to the lower edge of the attaching plate 13.

The front or striker plate 12 is of the same width as the anchor plate 18, and is provided 20 along its upper edge with spaced and rearwardly extending connecting arms or lugs 19, and along its lower edge with spaced and rearwardly extending connecting arms or lugs 20. These arms or lugs 19, 20 embrace the anchor plate 18 and 25 have their free ends 19^a, 20^a bent downwardly and upwardly around the plate 18 and seated in the recesses 14, 15, thereby connecting the front plate 12 to the anchor plate 18 in spaced relation thereto. Stop lugs 21, 21 extend from the ends 30 of the striker plate 12 and are bent rearwardly to close the ends of the cage B.

A plurality of arcuate plates C, preferably of thin spring steel and of less thickness than the front plate 12, but of substantially the same width as the front plate 12 and the anchor plate 18, are inserted separately side by side within the cage B prior to one of the stop lugs 21 being bent rearwardly. These filler plates C tightly fill 35 the cage but are spaced apart by air films which function to interrupt the sound waves when the abutment is struck by the type bar and thereby reduce the noise of impact.

The cage B is positioned in the recess 8 of the segment and is secured thereto by screws 22 45 which pass through perforations in the ears 16. Two of these screws serve to fasten the sheet metal guard plate 23 to the segment. By reason of the rear plate 13 being wider than and projecting below the front plate 12 and the filler plates C, the abutment assembly will readily fit the inclined lateral wall 9 of the recess 8 and will be thereby further retained in the segment.

It will be noted that the rear plate lies flat 55

against the vertical wall of the recess 8, and that this is made possible by the recesses 14, 15 in the rear plate which receive the ends 19^a, 20^a of the arms 19, 20.

5 It will also be observed that the method employed in forming my invention consists broadly in first forming an arcuate metal cage including a front striker plate, and then filling the cage with a plurality of relatively thin plates preferably of spring steel; that the cage is formed by first forming the front and rear plates, then rigidly securing the anchor plate to the rear plate, and then positioning the front striker plate in spaced relation to the anchor plate; and 10 that finally the stop lugs are bent rearwardly to retain the filler plates against endwise displacement.

From the foregoing, it will be seen that I have provided a self-contained abutment of sound-deadening and wear-resisting construction; that the abutment can be readily applied as a unit to or removed as a unit from the segment, and when in operative position the abutment is firmly seated throughout its entire length and consequently the abutment will react uniformly to the impacts of all the type bars.

I claim:

1. A type bar abutment comprising a cage including a front striker plate, a rear plate spaced from the front plate and being provided with spaced recesses along its upper and lower edges, an anchor plate rigidly connected to the front face of the rear plate and covering said recesses, said front plate having arms extending rearwardly from the upper and lower edges thereof and having their ends bent over the anchor plate and positioned in the recesses of the rear plate, and a plurality of noise-reducing filler plates mounted within the cage between the front and rear plates thereof.

2. A type bar abutment comprising a cage including a front striker plate, a rear plate spaced from the front plate and being provided with spaced recesses along its upper and lower edges, an anchor plate rigidly connected to the front face of the rear plate and covering said recesses, said front plate having arms extending rearwardly from the upper and lower edges thereof and having their ends bent over the anchor plate and positioned in the recesses of the rear plate, the upper arms being staggered with respect to the lower arms, and a plurality of noise-reducing filler plates mounted within the cage between the front and rear plates thereof.

3. A self-contained type bar abutment comprising a cage including a front striker plate, a rear plate spaced from the front plate, and upper and lower arms loosely connecting said plates, a plurality of noise-reducing filler plates mounted within the cage between the front and rear plates thereof, and being retained by and within said cage, the entire abutment comprising the cage, plates, and arms being attachable as a unit to and removable as a unit from a support.

4. A type bar abutment comprising a cage including a front striker plate, a rear plate spaced from the front plate and being provided with spaced recesses along its upper and lower edges, an anchor plate rigidly connected to the front face of the rear plate and covering said recesses, said front plate having arms extending rearwardly from the upper and lower edges thereof and having their ends bent over the anchor plate and positioned in the recesses of the rear plate, a plurality of noise-reducing filler plates mounted within the cage between the front and rear plates thereof, and stops extending rearwardly from the ends of the front plate for retaining the filler plates against endwise displacement.

5. The combination with a type bar segment having a central recess formed in its front face, said recess having a downwardly and rearwardly inclined lateral wall, and a type bar abutment mounted in said recess, said abutment including a front striker plate, a rear attaching plate, and a plurality of intermediate noise-reducing plates, the attaching plate being seated on the inner end of the inclined lateral wall, and the front and intermediate plates being of substantially the same width and having their lower edges disposed above the front edge of the lateral wall.

6. A self-contained sound-deadening type bar abutment adapted to be mounted on a type bar segment, said abutment comprising a front striker plate, a rear plate, connecting means extending between said front and rear plates for connecting them and limiting separating movement thereof but permitting movement of the plates relatively toward each other, and a plurality of filler plates interposed between said front and rear plates, the front and rear plates and said connecting means therebetween maintaining said filler plates in assembly with air films therebetween, the entire abutment being attachable as a unit to and removable as a unit from the type-bar segment.

HENRY J. HART.
